UNITED STATES PATENT OFFICE.

WILLIAM F. DEISTER, OF FORT WAYNE, INDIANA.

PROCESS AND APPARATUS FOR CLASSIFYING CRUSHED ORES.

1,071,715.

Specification of Letters Patent.

Patented Sept. 2, 1913.

Application filed January 30, 1913. Serial No. 745,169.

To all whom it may concern:

Be it known that I, WILLIAM F. DEISTER, residing at Fort Wayne, in the county of Allen and State of Indiana, a citizen of the 5 United States, have invented or discovered certain new and useful Improvements in Processes and Apparatus for Classifying Crushed Ores, of which improvements the following is a specification.

10 In obtaining values from metalliferous ores, it is necessary from a commercial standpoint, to separate the values from foreign materials as far as possible by mechanical means, and to this end the ores are 15 crushed as finely as possible and the values extracted by concentrating tables. In crushing the materials are not reduced to the same grade of fineness, and it is necessary to separate the coarser material from the finer, as 20 a concentrating table suitable for treating coarse material or "sand" is not equally efficient in treating the fine material or "slime."

25 The invention described herein relates to an improved form of classifier, whereby the materials as they come from the stamps or other comminuting mechanism may be graded according to their respective degrees of comminution.

30 The invention is hereinafter more fully described and claimed.

In the accompanying drawings forming a part of this specification, Figure 1 is a sectional elevation showing my improved classifier connected to a launder; Fig. 2 is a similar view showing a modification in the arrangement of the diaphragms; Fig. 3 is a sectional view showing a modification in the form of the diaphragms; Fig. 4 is a top plan 40 view of the classifier; Figs. 5 and 6 are plan views of modified forms of diaphragms.

In the practice of the invention the shell 1 preferably formed of cast-iron has its upper end connected to a discharge opening in 45 the launder 2, or conductor or receptacle of the crushed materials. The shell 1 is provided with a plurality of diaphragms 3 having openings therethrough, the openings in one diaphragm being preferably out of line 50 vertically with those in adjacent diaphragms and below, and of sufficient size to permit of the free passage of the coarser material entering the upper end of the shell. It is preferred that the diaphragms should be 55 made in the form of hollow cones as shown

in Figs. 1 and 2, and that these conical diaphragms should be arranged in inverted positions as shown in Fig. 1, although they may be placed in the shells with their apices pointing upward as shown in Fig. 2. Openings 4 are formed through the diaphragms, said opening being preferably elongated and intersecting at the center of the diaphragm. It has been found that the classifier will operate more efficiently, if the openings adjacent to the periphery of the diaphragms are made somewhat larger than those nearer the center. Where elongated openings or slots are employed, they are gradually increased in width from the center outwardly 65 as shown in Fig. 4.

While the diaphragms may be supported in the shell in any suitable manner, it is preferred that the inner wall of the latter should be provided with shoulders 5 on 70 which the edges of the diaphragms will rest. To insure the proper place of the diaphragms in the shell especially as regards the staggering of the openings in adjacent diaphragms a rib 6 is formed on the inner 75 wall of the shell to engage properly arranged notches in the peripheries of the diaphragm.

The area of the discharge opening 7 in the lower end of the shell will be varied in accordance with the quantity of coarse materials which are to be fed to the "sand" table. At a suitable point preferably intermediate the outlet and the lowest diaphragm the shell is provided with one or more water inlets 8. It is preferred that the water 80 should enter the shell opposite the blank portions of the conical diaphragm so that the solid materials passing down through the slots will not be materially diverted 85 from their line of movement. 95

In the operation of the classifier a portion of the crushed material which is mixed with sufficient water to insure its movement along the launder passes down into the shell and through the openings in the diaphragms. 100 At the same time sufficient water is admitted through the inlet 8 to insure an upward flow of water, the rate or force of this upward movement being adjusted in accordance with the grade of material to be discharged from the outlet of any particular classifier of the series, which is customary with the launder. It will be understood that as the rate of the upward flow of water is increased only such portions of the material 105 110

as have sufficient size and weight to overcome the upward pressure of water will pass on down through the diaphragm and outlet. As the coarse and fine material are thoroughly mixed as they enter the classifier, 5 and the fine portions will adhere to the coarse, the staggered path of the material through the shell will afford opportunity for the washing the fine portions off of the coarser.

10 The water flowing up through the shell will carry with it the finer material, the amount and grade of material so carried being dependent on the rate of upward flow.

15 The water and the materials thus carried up will enter the launder and pass on down to the next classifier.

As shown in Fig. 3 flat diaphragms may be employed and when used some of the material will bank up as indicated and thus give to some extent the guiding effect of the 20 conical diaphragms.

It will be understood that the water should not be admitted under such pressure 25 or have such a rate of upward flow as will produce material agitation, as the main function of the water is to prevent the downward movement of the finer material with as little interference as possible with the 30 downward movement of the coarser materials.

As is well known finely divided material will move down through a liquid more slowly when its constituents are more or 35 less separated than if in a more or less compact mass. This characteristic action is taken advantage of in the practice of my invention.

When the crushed material drops into one of the conical diaphragms the 40 constituent parts are directed to the openings or slots, through which they pass in a more or less compact stream. When passing from one diaphragm to another, the stream of crushed materials will be 45 more or less disrupted by the water moving in the reverse direction but the separated or loosened materials will be gathered together again by the second diaphragm.

The water in passing up through the slots 50 will be more effective in resisting the downward movement of the crushed materials, but such increased resistance is overcome by the gathering of the material into more or less compact streams as above described.

55 It will be readily understood that as the solid material cannot pass down below the diaphragm except through the openings, through which the water must also pass up, the solid particles are collected into comparatively dense streams when moving 60 through the openings in which they meet the water, the upward movement of which will be accelerated due to the difference between the transverse area of the shell and 65 the areas of the openings through the dia-

phragm. By reason of this collecting of the solid materials into relatively dense streams and the acceleration in the flow of water, the solid materials are subjected to a very effective washing action. The jet like action 70 of the water in passing through the openings has a double effect. It will cause the heavy solid particles to spread out after they have passed through the openings, into those portions of the body of water below 75 the diaphragms having a slower upward movement, and the light particles washed from the heavy particles by the accelerated jets, will be carried upward so as to be caught and carried along by the upward 80 movement of the water to the openings in the next diaphragm. By arranging the openings in the adjacent diaphragms out of line vertically the dispersive action of the water jets due to the openings will move the particles into line with the openings in adjacent 85 diaphragms.

I claim herein as my invention:

1. A classifier having in combination, a shell having an outlet at its lower end, a diaphragm extending across the shell, means for introducing water into the shell at a point intermediate the outlet and the diaphragm, the diaphragm having openings therethrough for the downward movement 95 of the solid materials and the upward flow of the water, and means for gravitally directing the solid materials into said openings.

2. A classifier for crushed materials having in combination, a shell having an outlet at its lower end, a series of diaphragms having openings therethrough arranged transverse of the shell, the openings in adjacent diaphragms being out of line vertically, and means for causing an upward flow of water through the shell, the water being admitted into the shell at a point intermediate the outlet and the diaphragms.

3. A classifier for crushed materials having in combination, a shell having an outlet at its lower end, a series of conical diaphragms having intersecting slots therethrough arranged transverse of the shell, and means for causing an upward flow of water 115 through the shell, the water being admitted into the shell at a point intermediate the outlet and the diaphragm.

4. A classifier for crushed materials having in combination, a shell having an outlet 120 at its lower end, a series of conical diaphragms having intersecting slots therethrough arranged transverse of the shell, with their slots out of line vertically, and means for causing an upward flow of water 125 through the shell, the water being admitted into the shell at a point intermediate the outlet and the diaphragms.

5. As an improvement in the art of classifying crushed materials, the method herein 130

described, which consists in discharging
crushed materials into an upwardly moving
body of water, dividing said material into
downwardly flowing streams, dispersing
such streams laterally by an acceleration of
the rate of movement of portions of the up-
wardly moving water, causing the dispersed
materials to gravitally converge into other

streams, and then dispersing the latter by
accelerating the movement of the water. 10

In testimony whereof, I have hereunto set
my hand.

WILLIAM F. DEISTER.
